APPARATUS FOR RESHAPING METAL ARTICLES

George Grimes, Rock Island, Ill.

Application September 14, 1945, Serial No. 616,437

13 Claims. (Cl. 153—32)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to apparatus for reshaping metal articles. More particularly the invention relates to apparatus for re-forming and realigning internal combustion engine manifolds.

In the overhauling and rebuilding of internal combustion engines, it is of course desirable to re-use as many parts as possible. However it is not always possible to re-use certain parts because of the fact that these parts have been subjected to such wear and deterioration as to be unsuitable for further use. Heretofore manifolds, particularly exhaust manifolds, were considered not usable, since in many instances they were warped and otherwise distorted because of the intense heat to which they were subjected in the operation of the engines of which they formed parts. According to the present invention, it has been found possible to reshape and realign such manifolds so that they may be used again. It has been found that the particular distortion occurring in certain manifolds is concentrated in a misalignment of the manifold branches caused by warping of the manifold body, with the result that the branch flanges are twisted to such an extent that they no longer occupy the same general plane. Because of this misalignment and distortion such manifolds could not be re-used, since the apertures in the flanges would no longer line up with the attached studs on the engine block.

The principal object of the present invention is to provide an apparatus for reshaping or re-forming such manifolds so that the branches thereof are properly realigned.

The invention has for another object the provision of an apparatus comprising a pair of relatively movable members to each of which a portion of the manifold may be attached so that the necessary bending or stretching forces may be easily and quickly applied to the manifold.

Still another object of the invention is to provide means for rigidly holding the branches in proper alignment while the manifold cools; it is specifically an object of the invention to provide these means as a plurality of adjustable wedge or spreader elements.

The foregoing and other objects and features of the invention will become apparent to those skilled in the art as the disclosure of a preferred form of the invention is more fully set forth below, reference being had to the accompanying sheets of drawings in which:

Fig. 1 is a plan view of the apparatus, with a manifold being shown in place thereon in broken lines;

Fig. 2 is a side elevational view of the structure shown in Fig. 1;

Fig. 3 is a transverse sectional view taken substantially on the line 3—3 of Fig. 1;

Fig. 4 is an illustration of a manifold showing one type of distortion most commonly encountered; and

Fig. 5 is a perspective detail view of one of the adjustable wedge or spreader elements.

The invention has been referred to above and will be described below in connection with its use and adaptability to the re-forming and realigning of internal combustion engine manifolds. However, it will be appreciated that the invention may be likewise employed in conjunction with the re-forming or realigning of similar metal articles. Consequently, it should be understood that the present disclosure is illustrative and not limiting.

The type of manifold shown in Fig. 4 comprises essentially a body 10 having a plurality of branches or ports 11, each of which is provided with an apertured attaching flange 12. This manifold structure is generally conventional and it will be understood that the invention is applicable to other manifolds that do not depart too radically from such conventional design. The type of manifold distortion most commonly encountered is indicated by the broken line A—A. It will be noted that there has occurred in the main body a bending on the longitudinal body axis so that the attaching flanges 12 of the branches 11 are displaced from their true positions in the same general plane, which plane is indicated by the line B—B. In order that a manifold so distorted may be re-used it is necessary that it be re-formed or reshaped so that the branches 11 are realigned; that is to say, so that the branches 11 are again parallel and so that the attaching flanges 12 again lie in the plane represented by the line B—B.

For the achievement of the result just described there is provided, according to the present invention, an apparatus consisting of a base 13 which is provided at one end thereof with a supporting plate or member 14 rigidly secured to the base by a plurality of bolts 15. The other end of the base 13 is formed with a pair of transversely spaced, longitudinal running guide members 16 rigidly secured to the base as by a plurality of bolts 17. As best shown in Fig. 3, each guide member is generally L-shaped in cross section and the two members provide a track in which is mounted a movable member or plate 18. This plate further slides on the upper surface of one end of the base 13 and is thus accurately guided on the base for longitudinal movement with respect to the supporting or stationary plate 14. One end of the plate 18 extends at the proximate end of the base 13 and rigidly carries a depending

cross member 19. The cross member 19 is formed with a threaded bore 20 disposed on a longitudinal axis and receiving therein a screw member 21 which has an operating handle 22 at its outer end. The screw member 21 abuts the proximate end of the base 13 and provides means by which the plate 18 may be moved with respect to the supporting or stationary plate 14.

As best shown in Figs. 1 and 2, the manifold is positioned on the apparatus with the main axis of the manifold parallel to the main axis of the apparatus; in other words, the longitudinal axis of the manifold body 10 extends in the direction of movement of the plate 18 with respect to the plate 14. The plates 14 and 18 are so disposed as to receive or have located thereon, respectively, one-half of the total number of branches 11. In the preferred form of the invention herein disclosed, the upper surfaces of the plates 14 and 18 are preferably flat and accurate to the extent that they represent the plane in which the branch flanges 12 will lie when properly aligned.

The type of manifold presently illustrated is shown as having four branches 11. Inasmuch as the usual internal combustion engine of the inline or V type consists of an even number of cylinders, the manifolds will ordinarily have an even number of branches; i. e., branches will occur in pairs or in multiples of two, except in those cases where the manifold may be provided with Siamese ports (two ports in one branch, as in the case of a manifold for a four-cylinder engine in which there are three branches, the first and third each containing a single part and the second or center branch containing a double part). For the present, the disclosure will be concerned with the type of manifold ordinarily encountered; i. e., a manifold with an even number of branches.

The stationary or supporting plate 14 is provided with a plurality of upstanding pins 23 arranged to correspond with certain of the apertures in the pair of flanges 12 on that pair of branches 11 lying to one side of the transverse center line of the manifold body 10. Each of these pins is provided with a definite taper so that it may easily enter the respective flange aperture. As previously stated, the distortion of the manifold ordinarily so affects the alignment of the flange apertures as to make difficult the removal of the manifold from its position on the engine block. Likewise, such distortion would substantially prevent mounting of the manifold on the aperture in the absence of the tapered locating pins 23. The plate 14 is further provided with a plurality of upstanding threaded studs 24, each of which is adapted to enter or be received by the remaining apertures in the flanges 12 of that half of the manifold located on the plate 14. Each stud 24 is adapted to receive a nut 25 by means of which the flanges 12 may be drawn down as tightly as possible on the plate 14. The plate 14 is provided with additional means for rigidly securing the proximate half of the manifold thereto. This means comprises a plurality of clamping elements each of which includes a clamp 26 and a securing bolt 27. The clamps 26 engage the upper surfaces of the flanges 12, and the bolts 27 are drawn down tightly.

The other half of the manifold structure is similarly rigidly attached to the movable plate 18, this plate being provided with a plurality of tapered locating pins 28, securing studs and nuts 29 and 30, respectively, and clamping elements including clamps 31 and securing bolts 32, each

of which is similar to the securing and clamping elements described in connection with the securing of the other half of the manifold to the plate 14.

5 The movable plate 18 is provided with a gage element or pointer 33 which is cooperable with an index mark 34 on one of the longitudinal guide members 16. There is thus provided means by which the operator of the apparatus may determine when he has moved the plate 18 sufficiently to re-form the manifold.

As previously stated, the invention contemplates also the provision of means for holding the branches 11 rigidly in proper alignment. A preferred form of this means is illustrated in perspective in Fig. 5 and will be referred to as an adjustable wedge or spreader element designated generally by the numeral 35. Each element 35 includes a first wedge block 36 having a threaded bore which receives an adjusting screw 37. The block 36 is supplemented by two additional, complementary wedge blocks 38, each of which is formed at its inner portion with a semi-cylindrical recess 39 formed on an axis concentric with the axis of the adjusting screw 37. The blocks 36 and 38 are held together, for the purpose of ease in handling, by a slotted connecting member 40, the opposite ends of which ride in grooves 41 formed respectively in the blocks 38. Two screws 42 pass through the slotted member 40 and are threaded respectively into the blocks 38. The screws are sufficiently loose so that the block 38 may have relative movement limited only by the extent of the slotted member 40. The semicircular recesses 39 in the blocks 38 embrace the adjusting screw 37 and thereby serve to keep the block 36 in position as part of the wedge assembly.

In the use of the preferred form of apparatus just described and in the performance of the preferred method for reshaping the manifold, the manifold is mounted on the apparatus in the manner previously described; i. e., one-half the number of branches 11 is located on the stationary or supporting plate 14, and the branches are secured in place thereon by means of the locating pins 23 and securing means 24-25 and 26-27. The remaining branches are secured to the movable plate 18 by means of the locating pins 28 and the securing elements 29-30 and 31-32. The next step in the method comprises heating the body portion 10 of the manifold. Heat may be applied to the manifold by an acetylene or blowtorch, for example, or the manifold may be placed in a furnace if desired. Next the members 14 and 18 are forcibly separated by means of the operating handle 22 and screw member 21. The member or plate 18 is moved away from the plate 14 until the gage or indicating member 33 on the plate 18 is lined up with the index 34 on the guide member 16, the necessary extent of movement having been determined beforehand. The adjustable spreader elements 35 are arranged between adjacent branches 11 of the manifold and by means of the adjusting screw 37 are drawn up tightly to maintain the branches 11 rigidly in their proper realigned positions. Spreading of the blocks 38 is effected by tightening of the screw 37, which draws the block 36 further between the blocks 38. The inner face of the head of the bolt or screw 37 bears against the proximate outer faces of the blocks, which cannot spread because they are restrained by engagement with adjacent manifold branches 11. The manifold is then allowed to cool and may be

left on the apparatus or may be removed therefrom and be allowed to cool while another manifold is being re-formed on the apparatus. It will be understood, of course, that the adjustable wedges 35 are left in place when the manifold is removed from the apparatus. The equipment included in such apparatus accordingly will preferably include several adjustable wedge elements 35.

In the use of the apparatus and the performance of the method herein described in connection with manifolds having Siamese branches or ports, it may be found necessary to vary somewhat the procedure outlined above. For example in a manifold of the type comprising three branches in which each end branch is a single branch and the central branch is Siamese, there will be little, if any distortion in the flange of the central branch. Therefore, a manifold of this type may be re-formed by bending or reshaping the manifold body by means of force applied to the end branches, very much in the manner of the operation described above with the exception that the central branch need not be rigidly secured to either of the plates or members 14 or 18. In the case of a manifold comprising two branches both of which are Siamese, the situation is substantially identical to that of a manifold which has four or any other even number of single branches.

Even in the case of a manifold of the type herein illustrated, it may be desirable in certain instances to secure only the end branches, or only the intermediate branches, to the plates 14 and 18; likewise, it may be desired to omit the central spreader element 35. Other variations in the design and use of the apparatus and in the performance of the method herein set forth may occur to those skilled in the art. It will be understood, of course, that these and other modifications and alterations may be made in the preferred form of the invention illustrated and described without departing from the spirit and scope of the invention as defined in the appended claims.

I claim:

1. Apparatus for reshaping and realigning metal articles such as internal combustion engine manifolds of the type consisting of a main body and a plurality of branches having apertured flanges, comprising a pair of forcibly separable members on which the manifold may be mounted with the axis of the body thereof lying in the direction of separation of said members and with half the number of branches being located on one of said members and the remaining branches being located on the other of said members, means respectively on each of said members including surface portions on which the branch flanges may seat, means respectively on each of said members including pins receivable by the apertured flanges of the branches, means on each of said members for rigidly securing the branches respectively to said members, means for forcibly separating said members, a plurality of adjustable wedge elements adapted respectively for insertion between adjacent branches of the manifold, and means cooperable between said members for indicating the extent of forcible separation thereof.

2. Apparatus for reshaping and realigning metal articles such as internal combustion engine manifolds of the type consisting of a main body and a plurality of flanged branches, comprising

a pair of forcibly separable members on which the manifold may be mounted with the axis of the body thereof lying in the direction of separation of said members and with half the number of branches being located on one of said members and the remaining branches being located on the other of said members, means respectively on each of said members including surface portions on which the branch flanges may seat, means on each of said members for rigidly securing the branches respectively to said members, means for forcibly separating said members, a plurality of adjustable wedge elements adapted respectively for insertion between adjacent branches of the manifold, and means cooperable between said members for indicating the extent of forcible separation thereof.

3. Apparatus for reshaping and realigning metal articles such as internal combustion engine manifolds of the type consisting of a main body and a plurality of branches having apertured flanges, comprising a pair of forcibly separable members on which the manifold may be mounted with the axis of the body thereof lying in the direction of separation of said members and with half the number of branches being located on one of said members and the remaining branches being located on the other of said members, means respectively on each of said members including surface portions on which the branch flanges may seat, means respectively on each of said members including pins receivable by the apertured flanges of the branches, means on each of said members for rigidly securing the branches respectively to said members, means for forcibly separating said members, and a plurality of adjustable wedge elements adapted respectively for insertion between adjacent branches of the manifold.

4. Apparatus for reshaping and realigning metal articles such as internal combustion engine manifolds of the type consisting of a main body and a plurality of flanged branches, comprising a pair of forcibly separable members on which the manifold may be mounted with the axis of the body thereof lying in the direction of separation of said members and with half the number of branches being located on one of said members and the remaining branches being located on the other of said members, means respectively on each of said members including surface portions on which the branch flanges may seat, means on each of said members for rigidly securing the branches respectively to said members, means for forcibly separating said members, and a plurality of adjustable wedge elements adapted respectively for insertion between adjacent branches of the manifold.

5. Apparatus for reshaping and realigning metal articles such as internal combustion engine manifolds of the type consisting of a main body and a plurality of branches, comprising a pair of forcibly separable members on which the manifold may be mounted with the axis of the body thereof lying in the direction of separation of said members and with half the number of branches being located on one of said members and the remaining branches being located on the other of said members, means on each of said members for rigidly securing the branches respectively to said members, means for forcibly separating said members, and a plurality of adjustable wedge elements adapted respectively for insertion between adjacent branches of the manifold.

6. Apparatus for reshaping and realigning

metal articles such as internal combustion engine manifolds of the type consisting of a main body and a plurality of pairs of branches having apertured flanges, comprising a pair of forcibly separable members on which the manifold may be mounted with the axis of the body thereof lying in the direction of separation of said members and with at least one pair of branches being located on one of said members and at least another pair of branches being located on the other of said members, means respectively on each of said members including surface portions on which said pairs of branch flanges may seat, means respectively on each of said members including pins receivable by the apertured flanges of said pairs of branches, means on each of said members for rigidly securing said pairs of branches respectively to said members, means for forcibly separating said members, and a plurality of spreader means adapted respectively for insertion between adjacent branches of said pairs of branches.

7. Apparatus for reshaping and realigning metal articles such as internal combustion engine manifolds of the type consisting of a main body and a plurality of flanged branches, comprising a pair of forcibly separable members on which the manifold may be mounted with the axis of the body thereof lying in the direction of separation of said members and with at least one branch at one side of the center of the manifold body being located on one of said members and at least one branch at the other side of the manifold body being located on the other of said members, means respectively on each of said members including surface portions on which the flanges of said branches may seat, means on each of said members for rigidly securing said branches respectively to said members, means for forcibly separating said members, and a plurality of spreader means adapted respectively for insertion between said branches of the manifold.

8. Apparatus for reshaping and realigning metal articles such as internal combustion engine manifolds of the type consisting of a main body and a plurality of flanged branches, comprising a pair of forcibly separable members on which the manifold may be mounted with the axis of the body thereof lying in the direction of separation of said members and with half the number of branches being located on one of said members and the remaining branches being located on the other of said members, means on each of said members for rigidly securing the branches respectively to said members, means for forcibly separating said members, and a plurality of spreader means adapted respectively for insertion between adjacent branches of the manifold.

9. Apparatus for reshaping and realigning metal articles such as internal combustion engine manifolds of the type consisting of a main body and a plurality of branches, comprising a pair of forcibly separable members on which the manifold may be mounted with the axis of the body thereof lying in the direction of separation of said members and with half the number of branches being located on one of said members and the remaining branches being located on the other of said members, means on each of said members for rigidly securing the branches respectively to said members, means for forcibly separating said members, and a plurality of spreader means

adapted respectively for insertion between adjacent branches of the manifold.

10. An adjustable wedge device comprising a first block having converging wedge surfaces, a pair of complementary blocks, each of which has a wedge surface cooperable with a respective wedge surface on said first block, means in said first block forming a threaded bore disposed on an axis bisecting said converging wedge surfaces of said first block, an adjusting screw threaded into said bore and projecting in the direction of convergence of said wedge surfaces, means on each of said complementary blocks forming a recess embracing said adjusting screw, means in each of said complementary blocks forming a groove transverse to the axis of said adjusting screw, a slotted connecting member having its end portions respectively fitting said grooves, and means loosely securing the end portions of said connecting member respectively to said complementary blocks.

11. An adjustable wedge device comprising a first block having converging wedge surfaces, a pair of complementary blocks, each of which has a wedge surface cooperable with a respective wedge surface on said first block, means in each of said complementary blocks forming a groove transverse to a line bisecting said converging wedge surfaces, a slotted connecting member having its end portions respectively fitting said grooves, means loosely securing the end portions of said connecting member respectively to said complementary blocks, and means cooperable between said first block and said complementary blocks for spreading said complementary blocks by introduction of said converging wedge surfaces between the wedge surfaces of said complementary blocks.

12. Apparatus for reshaping and realigning metal articles such as internal combustion engine manifolds of the type consisting of a main body and a plurality of branches, comprising a pair of forcibly separable members on which the manifold may be mounted with the axis of the body thereof lying in the direction of separation of said members and with at least one of said branches being located on one of said members and at least one of said branches being located on the other of said members, means on each of said members for rigidly securing said branches respectively to said members, means for forcibly separating said members, and means cooperable between said members for indicating the extent of forcible separation thereof.

13. Apparatus as set forth in claim 12, including means respectively on each of said members including surface portions on which flanges of said branches may seat.
